UNITED STATES PATENT OFFICE

HARUTYUN G. TERZIAN, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA

COMPLETE GASIFICATION APPARATUS

Application filed April 20, 1929. Serial No. 356,794.

The present invention relates to the complete gasification of bituminous fuel, with the recovery of a large portion of its volatile matter and the production of mixed 5 coal gas and water gas in a generator in which the bituminous fuel is carbonized in the upper portion of the generator by the passage through it of hot gases, and the resultant coke gasified in the lower portion.

10 In ordinary water gas practice with bituminous fuel, the blast gases as well as the up-run water gas are passed through the uncarbonized coal. This practice furnishes large volumes of hot gases to effect carbonization but has the disadvantage of not permitting the recovery of as great an amount of the volatile material in the fuel as may be desirable.

15 This has led to the provision of the so-called complete gasification generator, in which the blast gases resulting from air blasting the coke in the lower portion of the generator are led off intermediate the ends of the fuel bed, before their passage through 20 the uncarbonized fuel. Reliance for carbonizing the fuel is placed on the hot up-run blue water gas alone, or assisted by recirculated gas or superheated steam. Some carbonizing effect is also sometimes supplied 25 by passing the blast gases around the wall of the carbonizing zone, and transferring heat to the fuel through the wall.

Theoretically carbonization can be effected 30 by the hot up-run blue water gas, but it must be brought into intimate contact with the fuel, throughout the cross section of the column.

35 In the operation of present generators for complete gasification, the principal difficulty 40 has been the lack of such contact. Gases passed upward through a fuel column tend to follow the generator wall. This is the case even with coke fuel, but with coke the tendency is not so exaggerated as to impair 45 too seriously the operation of the generator. With bituminous coal, however, the tendency is very marked with the result that the gases pass upward principally through a narrow annulus at the wall and the carbonization of 50 the main body of fuel is effected by the slow

conduction of heat through the fuel from the wall inward. This results in the incomplete carbonization of the fuel in the center of the column by the time it reaches the water gas reaction zone. In some cases, the 55 fuel in the center descends to the grate in its original condition. This lack of complete carbonization of the central portions of the fuel column reduces the efficiency and capacity of the generator.

60 It is the principal object of this invention to provide apparatus which will be free from the above disadvantages, which will pass the hot carbonizing gases more uniformly through the bituminous fuel and effectively 65 carbonize it throughout the horizontal cross section of the column before it descends to the water gas reaction zone.

Other objects and advantages of my invention will be described in connection with the 70 drawing which forms a part of this specification and which shows a vertical cross section of a carburetted water gas set employing my invention.

75 Referring to the drawing.

1 generally indicates the water gas generator, 2 is the carburetter, 3 is the superheater and 4 the wash box. The generator fuel bed comprises the carbonizing zone 5 in its upper portion, and the water gas zone 6 in its lower 80 portion. 7 is an air blast supply, 8 is a steam supply.

The generator is provided with the lining 9 consisting of refractory and heat insulating material. Within the lining around the carbonizing zone is the wall 10. The wall is spaced from the lining forming the annulus 11. Upper and lower ports 12 are provided in the wall 10 connecting the annulus and the fuel bed. The lower row of ports is approximately at the top of the water gas zone.

85 The generator is provided with gas off-take 13 which takes the form of a hollow core suspended in the carbonizing zone and which has the ports 14 leading from the fuel bed to 90 its interior.

95 In the apparatus illustrated the annular chamber 11 is connected to the carburetter by a valved connection 15, and the gas off-take 13 is connected to the carburetter by the 100

valved connection 16. In the apparatus illustrated the valved connection 17 supplies secondary air to the carburetter.

The superheater is connected at its base 5 with the carburetter and at its top with the wash box through the connection 18 provided with the valve 19.

The base of the generator is connected to the wash box through the valved connection 10 20 which passes to the rear of carburetter 2 and superheater 3. 21 leads from the wash box to a place of storage or disposal. 22 is the superheater stack valve, 23 is a steam supply to the superheater and 24 an oil supply to the carburetter. 25 is a valved bleeder pipe leading from the carbonizing zone of the generator to the wash box.

In operation, with the valve in connection 20 closed, the water gas zone of the fuel bed 25 in the generator is blasted by air supplied through 7. The valve in connection 16 being also closed and that in connection 15 open, the blast gases pass through the lower row of ports 12 into the annular chamber 11 around 25 the carbonizing zone, and thence out of the generator and, in the apparatus illustrated, through the carburetter and superheater, where they are burned with secondary air from supply 17. The burned gases exit 30 through the stack, valve 22 being open.

The air blast is then shut off, the valve in connection 15 is closed, while that in connection 16 is opened, and valve 19 remains open, and an up-run may be made with steam supplied at 8. The steam passes up through the water gas zone and owing to the density of the fuel bed a portion of the resultant water gas passes out through the lower ports 12 into the annular chamber 11 and from thence back 40 through the upper ports 12 into the fuel in the carbonizing zone, through it and into the off-take 13 through the ports 14. From the off-take 13 the gas passes into the carburetter where it may be carburetted with oil supplied 45 at 24 and fixed in the superheater as the gas passes therethrough to the wash box.

The steam may then be shut off at 8, valve 19 and the valve between connection 13 and connection 16 closed, the valves in connections 15 and 20 opened, and a down-run made with steam admitted at 23. The steam passes through the superheater and carburetter and from thence into the water gas zone of the generator through the annular chamber and 55 the lower row of ports 12. The resultant water gas passes through the connection 20 to the wash box. 26 is the opening for charging solid bituminous fuel, coal, wood, etc. to the generator. 27 is an ash pit door, 28 is a 60 cleaning door.

The provision of the annular chamber around the carbonizing zone of the generator with its lower ports leading from the fuel bed at or near the top of the water gas zone, 65 and its other ports leading directly into the

carbonizing zone at different levels, together with the ported central off-take, permits the passage of the hot up-run water gas through the entire horizontal cross section of the fuel column and provides more uniform and intimate contact across this section. It obviates the tendency for these carbonizing gases to flow up a narrow annulus in the proximity of the wall, and by contacting the gases with the fuel in the interior of the column, effects its 70 carbonization before it reaches the water gas zone. 75

Though some of the up-run water gas may flow directly to the ports in the central off-take, the greater portion flows first into the annulus and then transversely across the carbonizing zone. 80

The passage of the air blast gases through the annular chamber around the carbonizing zone, maintains the wall 10 at an elevated temperature and assists in carbonizing by heat radiated to the fuel and conducted inward. The heated wall insures the rapid coking of the fuel in contact with it, and prevents the sticking of the fuel to the wall. 85 90

During the air blasting, some coal gas is evolved in the carbonizing zone, and this gas may be bled off to the wash box through the valved bleeder pipe 25.

The central off-take may be formed of heat 95 resisting metal or may be of refractory or of metal faced with a refractory. The use of a refractory has the advantage of providing for the storage of more heat in the core and its radiation to the central portion of the fuel 100 column. 105

The invention has been described in connection with a carburetted water gas set for illustration. It may be used in a blue water gas set as well.

I claim:

1. A complete gasification apparatus for the manufacture of water gas including, in combination, a water gas generator having a gasification chamber and a carbonization chamber therein, an annular chamber surrounding the carbonization chamber, steam inlet means through said annular chamber to said generator, a perforated wall between the carbonization chamber and the annular chamber, ports between the gasification chamber and the annular chamber, and a perforated tubular off-take for gas located within the generator in the axis of the carbonization chamber and out of the gasification chamber. 115 120

2. A complete gasification apparatus for the manufacture of water gas including, in combination, a water gas generator having a gasification chamber and a carbonization chamber therein, an annular chamber surrounding the carbonization chamber, a carburetter, a valved connection between said annular chamber and said carburetter, steam inlet means through said annular chamber and 125 130

said carburetter to said generator, a perforated wall between the carbonization chamber and the annular chamber, ports between the gasification chamber and the annular chamber, a perforated tubular off-take for gas located within the generator in the axis of the carbonization chamber and out of the gasification chamber, and a valved connection between said gas off-take and said carburetter.

3. A complete gasification apparatus for the manufacture of water gas including, in combination, a water gas generator having a gasification chamber and a carbonization chamber therein, an annular chamber surrounding the carbonization chamber, a heat regenerating vessel, a valved connection between said annular chamber and said heat regenerating vessel, steam inlet means through said annular chamber and said heat regenerating vessel to said generator, a perforated wall between the carbonization chamber and the annular chamber, ports between the gasification chamber and the annular chamber, a perforated tubular off-take for gas located in the generator in the axis of the carbonization chamber and out of the gasification chamber, and a valved connection between said gas off-take and said heat regenerating vessel.
